COMPENSATING SUPERHEATER

Charles W. Gordon, Munster, Ind., assignor to
The Superheater Company, New York, N. Y.

Application December 3, 1932, Serial No. 645,546

3 Claims. (Cl. 122—480)

My invention relates to an arrangement whereby the operators may regulate the final temperature of steam from a boiler with convenience and accuracy. In my prior Patent No. 1,959,100, granted May 15, 1934, I have disclosed two arrangements whereby the final temperature of superheated steam may be controlled within close limits. Arrangements according to the present invention fall within the scope of the claims of 5 my prior patent.

It is one of the objects of the said invention to provide an arrangement adapted to be readily installed in Stirling type boilers already in use.

In order that my invention, together with its 15 objects and advantages, may be fully and readily understood, I will now describe in detail by way of example and in connection with the accompanying drawing, a superheater boiler selected from a number of possible embodiments of my 20 invention. In the drawing:

The figure is a vertical sectional view of a boiler in accordance with my invention. In the arrangement illustrated, 10 indicates as a whole a boiler of the Stirling type having a setting 11 including the usual roof 11a, a front upper drum 12, a rear upper drum 14 and a lower drum 16. Drums 12 and 16 are connected by a front group of generating tubes 18, 18 as well as by a rear group of generating tubes 20, 20. A baffle 21 is 25 shown extending upwardly from the drum 16 part way to the drum 12 and lying near the front edge of the group of tubes 20. It will be seen, that the two groups of tubes 18 and 20 may be regarded as a bank divided near its middle by the 30 baffle 21. However, the front group of tubes 18 may be staggered, if so desired, whereas the rear group of tubes 20 are necessarily arranged in rows to provide lanes permitting the insertion 35 between the rows of tubes 20 of a group of superheater units one of which is shown at 22. Drum 16 is connected to drum 14 by a rear bank composed of tubes 24, 24, the drums 12 and 14 being connected by circulators 26 and 28 in the usual manner to provide for steam flow and thermal 40 circulation of water in the boiler. The tubes 18 and 20 are somewhat inclined to the vertical whereas the tubes 24 are nearly vertical, this being a common arrangement. It results, however, that a considerable space 29 is left between the 45 tubes 20 and the tubes 24. In the space 29, I employ a second group of superheater units one of which appears at 30. The units 22 and 30 lie 50 nearly at the same level and a baffle 32 extends between the two groups of units. The upper end 55 of the baffle 32 is nearly at the same level as

baffle 21 and baffle 32 runs downwardly parallel to baffle 21 to a line near the lower ends of the units 30. At such line, baffle 32 runs rearwardly substantially horizontal thru an opening in the rear wall in the boiler setting dividing said opening into two gas outlets 34 and 35. A damper 36 is provided for controlling the flow of gases thru outlet 34 and a damper 37 is provided for controlling the flow thru outlet 35. Damper 36 is independent of the position of damper 37 and 10 each such damper has its independent adjusting means whereby the attendant is able to set dampers 36 and 37 so that the total volume of gases may be divided between outlets 34 and 35 in any desired proportion. As illustrated, two 15 sets of worm gearing 38 and 39 are provided for operating dampers 36 and 37 respectively.

Preferably the heating surface in the group of units 22 is a little less than half than that in group 20 30, but I do not limit myself to this. The heating in one group should, however, always be made less than that in the other. It is clear from the drawing, that gases which have passed thru the front tubes 18 and around the upper edge of baffle 21 may then follow either one of two paths 25 thru the rear portion of the boiler, one path running downwardly and then horizontally thru superheater units 22, the lower portion of bank 24 and the outlet 34, and the other path running downwardly thru units 30 and then horizontally 30 thru the upper portion of tubes 24 and the outlet 35. The lower such path is indicated on the drawing by reference character 49 and the upper by reference character 52. It is evident that the 35 gas flows in paths 49 and 52 are identical with those thru outlets 34 and 35 respectively so that dampers 36 and 37 may be used to vary the percentages of the total gas flow in the two paths 49 and 52.

The boiler 10 is shown as associated with a furnace chamber 44 lying below and somewhat in front of the tubes 18. I have illustrated on the walls of furnace 44 two groups of radiant type superheater units 46 and 48 respectively. In the arrangement illustrated steam is taken from 45 drum 14 by pipe 45. Some of the steam from pipe 45 is passed thru the units 46 and some thru the units 48, such units being connected in parallel as clearly appears from the drawing. However, units 46 may be in series with units 48 with 50 in my invention.

Steam from units 46 and 48 is conducted by pipe 50 to the units 22 and after passing thru units 22 the steam passes thru units 30 and then to the discharge pipe 52. While I have shown 55

units 22 in series with units 30, such groups of units may be in parallel within the invention. By varying the percentage, parts of the total gas flow passing thru path 40 and path 42, the final 5 temperature of the steam in pipe 52 may be varied or maintained constant as desired. Ordinarily, it is desired to maintain the steam temperature constant or nearly so irrespective of the load. The radiant type elements 46 and 48 co- 10 operate with the units 22 and 30 to decrease the amount of regulation required to maintain a substantially constant temperature at the point 52 irrespective of the load. However, I do not limit myself to the use of such radiant type units. 15 Furthermore, placing the units 22 in rows in a group of tubes such as 20 is preferable in that it increases the effect of changing the ratio between the gases in the path 40 and those in path 42. However, I do not limit myself to using tubes 20 20 and they may be omitted if desired. Preferably, an economizer 54 is placed in the gas flue 56 which receives gases from outlets 34 and 35.

It will be seen I have provided an arrangement 25 permitting regulation of the final steam temperature of a superheater boiler which is very compact and efficient and can be inserted into boilers already built and not designed with such regulation in mind.

While I have described a given boiler installation in detail, it will be understood that the claims 30 are to be construed broadly and not to be limited by the description of the drawing.

What I claim is:

1. The combination of a boiler having a water 35 drum, an inclined front bank of generating tubes

extending upwardly from said drum, a second bank of generating tubes extending upwardly from said drum and lying rearwardly from first said bank, means connecting the upper ends of said banks to provide a thermal circulation there- 5 thru, a baffle running upwardly from said drum parallel to the tubes of said first bank, a second baffle at the rear of said first baffle and parallel to it in part but having a horizontal part extending thru said second bank, two groups of 10 superheater units, one of said groups lying immediately at the rear of said first baffle and the other of said groups lying at the rear of and above said second baffle, said group between said baffles having less heating surface than the other 15 group, and means whereby the relative amounts of gases flowing in said paths may be varied.

2. The combination as set forth in claim 1 and in which the front baffle and the front bank of tubes are so arranged that the units of the 20 smaller groups of superheater units are inter- spersed among rows of generating tubes.

3. The combination of a Stirling type boiler having a setting provided with a roof, a baffle set back of the front generating tubes but substan- 25 tially parallel thereto, a second baffle set parallel to said first baffle for a portion of its own length and then extending transversely of the rear row of generating tubes of the boiler and forming with said first baffle and said roof two gas paths in 30 parallel, superheater surface in at least one of said paths, and independently operable dampers for controlling gases in said paths.

CHARLES W. GORDON. 35
